UNITED STATES PATENT OFFICE

109,911

DESIGN FOR A TIRE

Ben Goodman, Baltimore, Md.

Application March 18, 1938, Serial No. 75,934

Term of patent 14 years

To all whom it may concern:

Be it known that I, Ben Goodman, a citizen of the United States, residing at Baltimore, in the county of Baltimore and State of Maryland, have invented a new, original, and ornamental Design for a Tire, of which the following is a specification, reference being had to the accompanying drawing, forming part thereof.

Figure 1 is a plan view of a section of a tire showing my new design.

Figure 2 is a transverse sectional view.

Figure 3 is a fragmentary longitudinal sectional view taken on the line 3—3 of Figure 1.

I claim:

The ornamental design for a tire as shown.

BEN GOODMAN.
